BANDING MACHINE

Edward C. Sloan, Geneva, and Wilton F. Hoag, Batavia, Ill., assignors, by mesne assignments, to Kartridg-Pak Machine Co., Chicago, Ill., a corporation of Illinois

Application June 26, 1942, Serial No. 448,672

26 Claims. (Cl. 93—2)

1

This invention has for one object to provide means for securing a wrapping about a plurality of objects. In the particular form here shown, it has for one object to provide means for placing a band about a sausage or for placing a continuous band around a plurality of sausages, which become thereby connected by the band. Another object is to provide means for securing a continuous band about a plurality of generally similarly shaped objects.

A still further object is to provide means for bringing together about a plurality of sausages a pair of bands and for positioning each band partly about each sausage and for thereafter securing the bands together so that each band is joined to the other at points separating the sausages.

A still further object is to provide in connection with the joining means means for partially severing or slotting or notching that part of the bands which is joined between the sausages to facilitate separation or tearing.

Other objects will appear from time to time throughout the specification and claims.

This invention is illustrated more or less diagrammatically in the accompanying drawings, wherein:

Figure 1 is a side elevation of one form of the device.

Figure 2 is a section taken on an enlarged scale at line 2—2 of Figure 1, with parts omitted.

Figure 3 is a longitudinal, vertical, sectional detail taken on an enlarged scale at line 3—3 of Figure 2, and showing the joining means in the raised position.

Figure 4 is a view similar to Figure 3, showing the joining means in the lowered position.

Figure 5 is a longitudinal, horizontal section taken at line 5—5 of Figure 4.

Figure 6 is a sectional detail taken at line 6—6 of Figure 4.

Figure 7 is a detailed elevation illustrating a portion of the driver which is shown in Figures 3 and 4, but from the side opposite to those figures.

Figure 8 is a side elevation showing a portion of the mechanism of Figure 7 in a modified position.

Figure 9 is a vertical sectional detail taken on an enlarged scale at line 9—9 of Figure 5.

Figure 10 is a transverse, sectional detail taken at line 10—10 of Figure 9.

Figure 11 is a transverse, vertical, sectional detail taken at line 11—11 of Figure 9.

2

Figure 12 is a plan view of a finished assembly of banded sausages.

Figure 13 is a transverse, vertical, sectional view taken on an enlarged scale at line 13—13 of Figure 8.

Figure 14 is a view similar to Figure 3 showing the modified form of spring member.

Figure 15 is a view similar to Figure 4 showing the modified form of Figure 14.

10 Like parts are indicated by like characters throughout the specification and the drawings.

The device of this invention in the particular form here shown comprises in general a framework or supporting means, an article conveying means, together with a drive for moving it, and in addition a pair of means for supplying bands, and means for causing the bands to be fed progressively toward the article, and finally means for moving the bands together to join them intermediate the articles, and to secure them together. In the particular form here shown the securing means is a heat sealing means, and the bands are each provided with adhesive on one side, so that they may be readily sealed to each other.

15 20 25 As shown, the supporting means includes a plurality of legs or generally upright members 1, which are joined by longitudinal members 2, 2 and transverse members 3, 3. A shelf may be positioned on these members or additional transverse members 4, 4 may be used to carry the necessary driving means. As shown, the members 4, 4 support a motor 5 from which a shaft 6 projects. The shaft is connected by a coupling 7 to the shaft 8 of a geared reducer 9 which may be of any desired form, from which a shaft projects upon which is mounted a pulley 10. Obviously, other driving means might be arranged upon a shelf or upon the supports 4.

Members are provided at the upper end of the 40 upright members 1 to be carried by those members and to support and in part enclose the mechanism of the banding machine. As shown, these members include a pair of generally flat pieces 11, 11, which are supported at or near the

45 upper ends of the members 1. An article discharge apron may be secured at the discharge end of the assembly, and as shown particularly in Figures 1, 2, 3, and 4, includes side portions 12 and a top or material receiving portion 13 which may be integral with the side portions 12. This member 12, 13 is secured to the frame members 11, and is preferably inclined downwardly, and serves as a receiving and discharge surface for the banded sausages or other articles.

55 A supporting frame or extension 14 may be

secured to or supported from one of the members 11, and it serves as a support for the sealing means and also as a support for an arm 15, which carries a shaft 16, upon which a roll 17 of tape or paper may be positioned. As shown, the strip 18 of tape or paper is fed from the roll 17 to the point of use, and comprises the uppermost strip of material so fed and used.

An additional supporting member 19 may be mounted upon the device, and as shown particularly in Figures 7 and 8, it is secured at its lower end upon an extension 20, which may be supported from or formed integrally with one of the members 11. It is to be understood that the frame members 11 may be of almost any desired shape. They may comprise simple flat members which are positioned parallel to each other, or they may have parallel portions separated from each other by a given distance, and they may include portions supported from them and separated from each other by a greater distance. The portion 20 is thus shown as being generally a continuation of one of the members 11, while the portion 21, although supported preferably from the opposite member 11, is spaced outwardly from it by a web or portion 22. The exact arrangement and positioning of these parts depends obviously upon the convenience of manufacture and assembly, as well as upon the quantity of material required and the size of the members which must be assembled together to provide movements suitable to carry out the desired operations upon articles of the size with which the machine is to be used.

The means for conveying the articles, in this case sausages or generally similar articles, will now be described. A pair of chains 23, 23 is mounted, each upon suitable sprockets. As shown, there are at the upper left end of Figure 1 two sprockets 24, 25, the sprocket 24 being mounted on a short shaft which is supported in a bearing 26 carried by one of the frame members 11, and the sprocket 25 being mounted on a longer shaft 27 which is carried in a suitable bearing formed in or carried by the opposite frame member 11, and has secured on it a cam 28 which appears in elevation in Figures 7 and 8, and in top plan view in Figure 2. At the opposite end, the chains 23 are supported upon idler sprockets 29, which are mounted upon a shaft 30, which is supported in bearings 31, 31, which are themselves supported in the members 11 and might be supported on the frame in any desired manner.

At the end opposite the sprockets 29, and preferably below the sprockets 24 and 25, is a pair of driving sprockets 32, which are mounted on a shaft 33, which is supported in bearings 34, carried by the side members 11. At one end, as shown in Figures 1 and 2 in particular, the shaft 33 carries a gear 35 which meshes with a gear 36, which acts as an intermediate gear and is supported on a stub shaft 37. The gear 36 meshes with a pinion 38 on a shaft 39, which is carried in bearings on the members 20 and 21. It will be noticed that the pinion 38 is on the outside of the member 21. On the opposite side of the member 20—that is to say, on the outside of the member 20—as shown particularly in Figure 7, and fixed on the shaft 39, is a gear 40. Fixed also on the shaft 39, and positioned outwardly with respect to the gear 40, is a pulley 41, which is engaged by a driving belt 42, and this belt is driven from the pulley 10 of the gear reducer 9, as shown in Figures 1 and 2.

As will be seen particularly in Figures 7 and 8,

the gear 40 meshes with a gear 43 which is mounted on a shaft 44, supported in suitable bearings on the extension 20. The shaft 44 carries a cam 45, which is provided with an irregularly shaped internal cam face 46. Thus the rotation of the gear 40 rotates the gear 43, and the cam face 46. The gear and the cam may be fastened to each other and mounted for rotation on the shaft 44, or they might be otherwise constructed, so long as rotation of the gear 43 accomplishes rotation of the cam.

Positioned loosely about the shaft 44 is a yoke 47, with an opening 48, which, as shown particularly in Figures 7 and 8, is longer than it is wide, to permit an up and down movement of the yoke. The shaft acts as a bearing for the yoke. Pivoted in the yoke 47 is a cam engaging roller 49, which engages the cam face 46. The yoke itself is joined, as at 50, to the lower end of a plunger 51, and arranged to slide up and down in a bearing 52, which is mounted upon one face of the member 20. The yoke and plunger are urged upwardly by a spring 53, which is secured upon a pin 54, or any other suitable engaging member. As here shown, the pin 54 is mounted upon the member 15. At its lower end, the spring 53 engages the eye 55 of a member 56, which is attached to or secured in the yoke 47.

Adjacent its upper end, the plunger 51 is fixed to a member 57, which carries a bearing 58, in which a pin 59 is received. This pin is mounted in a disc 60, which is fixed on an arm 61. As shown in Figures 7 and 8 and 13, the arm has a downwardly depending reduced portion 62, and a hook-like member 63, which is adapted, in the lowermost position, to engage a pin 64, which has an enlarged head 65, which may be flattened on its upper surface, as shown in Figures 7 and 8. As shown in Figure 13, the member 60 is cut away or reduced on one side to permit the member 60 to clear the head 65 of the pin 64 in its lowermost position.

The upper end of the member 61 is shown in Figures 3, 4, 7, and 8, and 13. As shown in Figures 5, 7, and 8, the member 61 carries secured to it an irregularly shaped member which includes a number of parts. These include an arm 66, an angularly disposed portion 67, and an arm 68, which as shown particularly in Figures 7 and 8 lies generally parallel to the arm 66 and is inclined upwardly from it. The arm 68 is welded or otherwise secured to the member 61, and carries adjacent its outer end a cam engaging pin 69, which is engaged in a cam slot 70 formed in the member 14.

Movably positioned within the cam groove or cam portion 70 is a guiding dog 71, carried on an arm 72, pivoted at 73 on the member 14. The lever 72 is normally held against the stop 74 by a spring 75.

At the lower end of the arm 66 is pivotally mounted an adjustable arm 76, which has a cam engaging portion 77. At or near its free end, the member 76 is adjustably fixed in position by a pair of screws 78, 78, each of which is screw threaded in a lug 79, carried by the member 66.

As shown in Figure 5, the arm 61 is mounted between one of the members 11 and the member 14, which is spaced away from it, and in its movement it is guided by the arm assembly formed of the arms 66 and 68 and by the pin 69.

Secured adjacent the upper end of the arm 61 is a laterally extending support 80. This arm or support carries a sub-assembly, which includes

a heat sealing means and a perforating means, which will now be described. This mechanism is shown in vertical section in Figure 3, in elevation in Figures 4 and 13, and in sectional detail in Figure 9. The frame for the sub-assembly just mentioned includes a member 81 and a member 82. These may be integral, and may be disposed at right angles to each other. Secured in the member 81 are pins 83, which are received in suitable perforations in the member 80. The member 80 is provided with a screw threaded perforation to receive a sleeve 84, which is provided with a knob 85 by means of which it may be turned. The knob may be roughened or knurled, or provided with depressions 86 to receive a turning tool. This sleeve bears at one end against the member 81, and receives a bolt 87, the head of which is received in a suitable depression in the member 81. The bolt is drawn tight against the sleeve 84 by a nut 88. A lock nut 89 may be provided to engage the exterior of the sleeve 84.

The member 82 is grooved on its sides or otherwise shaped to receive lugs 90. These lugs are preferably an extension of side members 91, which are joined by a cross member 92 and are also joined by a member 93. Together, the members 90, 91, 92, and 93 form a frame, which carries the sealing and perforating means. This frame is adjustably supported from the member 82 by a threaded sleeve 94 having a head 95, which has depressions 96 to receive a turning tool. The sleeve 94 bears against the cross member 92, and is drawn down tight on it by a bolt 97, which is engaged by a nut 98.

The member 93 may be enlarged as at 99 to receive a heating element 100. Wires 101 furnish current to the heating element which is electrical, and is shown in detail in Figure 9. A member 102 extends downwardly from the enlargement 99, and this member is preferably provided with teeth 103.

Slideably positioned about the member 102 is a sheath or enclosing portion 104. It is secured to an arm 105, which has fixed in it a pair of pins 106. These pins pass through a guiding member 107, which is secured to the member 93. About each of the pins is positioned a spring 108, which urges the member 104 downwardly, when free to do so. A stop 109 is positioned in the upper end of the pins.

Associated with the sealing and perforating mechanism just above described is an article retaining means, which is shown in side elevation in Figures 3 and 4, and in plan view in Figure 5. It is also shown to some degree in Figures 6 and 7, and a portion of it is shown in Figure 9. This mechanism is supported on the member 19. It includes a relatively longitudinal frame member 110, which has at one end a downwardly depending member 111, and at the opposite end it has a downwardly depending member 112, which is provided with a perforation or opening 113.

A sliding sub-frame assembly is carried on the member 110, and includes a lower portion 114, from which lugs 115 and 116 extend upwardly. It will be seen from Figure 5 in particular that the lugs 115 and 116 are positioned on opposite sides of the member 110. The member 114 includes an apertured block 117, against which one end of a threaded sleeve 118 bears. This sleeve is mounted in an interiorly threaded member 119, which is secured to the part 110. This member 119 may be mounted for lateral movement along the part 110, but so engages the mem-

ber 110 that it cannot be separated upwardly from it. A lock nut 120 may bear against the member 119 and is in threaded engagement with the exterior of the sleeve 118. A bolt 121 extends through a perforation in the member 114, through the member 117, and the sleeve 118, and receives and is adjustably held in place by a nut 122. By means of the construction just described, the sub-frame 114, together with its lugs 115 and 116, may be adjustably positioned up or down with respect to the member 110, and may be locked in suitable adjusted position.

The member 117 receives and is secured to the end of a rod 123. This rod is threaded as at 124, and passes through a suitable perforation in the member 111. It is held in adjusted position by the nuts 125 and 126. By this means, the sub-frame 114 with its associated parts, may be adjusted to the right or the left from the position shown in Figure 3.

A stud 127 is positioned on the member 111 and as shown in Figures 3, 4, and 5 projects laterally from that member. A retaining member 128 is movably mounted on the stud. It is slotted as at 129, and this slot engages the stud. A spring 130 has one end secured, as at 131, to one end of the retaining member 128. At its other end, the spring is secured as at 132 upon an arm 133, which projects from the member 110. The retaining member 128 is provided with a downwardly curved portion 134, which passes through the opening 113 in the member 112. At its right-hand end, as shown particularly in Figures 3, 4, and 5, and in detail in Figure 9, the portion 134 is provided with a further downwardly curved hook portion 135. Fixed on the portion 134 is the base 136 of an upwardly and downwardly extending hook member 137. Positioned on the member 111 and in line with the member 131, to which one end of the spring 130 is attached, is an adjustable stop 138. This stop limits the travel of the member 128 and the parts which it carries, and is adjustable. At one limit of the travel of the member 128, the member 131 strikes the stop 138.

Secured also to the sub-frame member 114 is an arm 139, to which is secured a spring 140. A spring 141 is also secured to the member 139. As shown in Figure 5, the spring 140 is preferably provided with a pair of outwardly extending arms or fingers 142. The shape of the spring 140, 142 may be widely varied. As shown herewith, the fingers 142 are separated in order to provide separated points of contact with the articles which are being banded. If desired, these fingers may be provided with anti-friction members, such as rollers or the like, to hold the article in place and to eliminate or reduce friction.

It is to be understood that the exact shape of these parts depends upon the size and shape of the article which is to be handled, and similarly the chains 23 as shown are arranged to carry members 143. These are curved members and therefore provide receiving portions for the articles 144. As shown, the articles may be considered as sausages to which the bands are to be applied, and since they are generally round, it is suitable to form the members 143 to provide generally rounded depressions or pockets. If articles of other shapes were to be handled, the members 143 might be a different form particularly adapted to receive and handle the articles to be treated. The members 143, particularly as shown in Figure 4, provide what is in effect

a pushing portion, to force the sausage 144 forward to the point of banding, as the chain links move downwardly about the sprockets 24, 25.

The banding means includes an upper supply roll 17 supported on a shaft 16, carried from the member 15. Extending outwardly from the member 15 is a support 145, as shown particularly in Figure 1. Secured to this member is a curved guide 146 which includes an upper loop 147 and a lower loop 148. A friction roller 149 may be mounted on an arm 150, which is pivoted at 151 and is yieldingly held against the tape by a spring 152. The tape 18 is fed from the lower loop 148 to the point of use, as shown in Figure 4.

A second or lower tape is carried upon a drum 153, which is supported on a shaft 154, carried by an arm 155. The lower tape 156 runs over a guide 157, which is provided with a curved lower loop 158, an intermediate loop 159, and an upper loop 160. The guide 157 is supported as at 161 and 162. The details of its support are not important, as it might be carried by any means. A friction roller 163 is carried on an arm 164, pivoted as at 165. The arm 164 is adjustable by means of a screw 166 to vary the friction and the tension exerted upon the tape. The lower tape 156 moves from the upper loop 160 to the point of use, as shown particularly and in detail in Figures 3 and 4.

A wheel or roller 167 is mounted on a shaft 168, and is preferably provided with peripheral flanges 169. Between these flanges is provided a resilient member 170, which may be of rubber or other relatively yielding material. As shown in Figures 3 and 4, the shaft 168 is associated with a boss 171, which is cut away, as at 172, to provide a clearance for the members 143 of one of the chains 23. The roller 167 idles and is rotated by the pressure of the sealing and perforating member, as it moves downwardly toward and against it.

The invention is not limited to the exact details of the frame and supporting members. A guide, for example, might be added to one or both of the members 11 to assist in guiding and centering the sausages or other articles which are carried by the machine. These members have been omitted to simplify the showing generally.

The tape may be of many different sorts. It may be heat sealing or pressure sealing. It may be provided with printing on one or both sides. It may be of paper or fabric or any desirable material, such as Cellophane or other synthetic materials. It may be wide or narrow, and if desired, more than one set of tapes might be applied, so that when the articles leave the machine, they are secured by two separate sets of tapes, and each article would thus be engaged by two loops of paper. One suitable form of banding material comprises strips of paper or paper tapes, which are provided with glue on their contacting faces, and this glue is such that when heat and pressure are applied, it seals the two tapes together where they are in contact with each other.

It will be realized that whereas we have described and shown a practical and operative embodiment of our invention and the method for carrying it out, nevertheless many changes may be made in the size, shape, number and disposition of parts, and in the details and steps of such method without departing from the spirit of our invention. We therefore wish our description and drawings to be taken as in a broad

sense illustrative or diagrammatic, rather than as limiting us to our precise showing.

As shown in the modified form of Figures 14 and 15 there is substituted instead of the relatively stiff spring member 134 and its point 135 a lighter or more flexible spring member 174, which as shown has a point or end 173, and this latter is shaped in two curves, divided at the point 175. This form of spring extends farther to the right in the machine than does the spring 134, 135, as shown in Figures 3 and 4. It extends well under the heating assembly and is contacted by the assembly as the latter descends and is, therefore, moved downward with the heating assembly and its end 173 is caught or held between the sausage and the heating assembly, so that the effect of the heating assembly in moving the sausage to the left is wholly or largely transmitted through the spring end 173 and the sausage, or whatever article is being banded in the machine, is safeguarded against tearing, pinching or other injury which might occur if it were contacted directly by any part of the heating assembly.

While the spring 174, 173 might extend clear to the left as does the member 128, 134 of Figure 3, it is preferable to have the spring supported on a somewhat rigid member, and the rigid member is the supporting part and the spring is the added part, which differs from the construction of Figure 3 in which the spring is integral with the supporting part.

Thus instead of the member 134 there is provided a member 176, which is attached to, or made integral with the member 128. The member 134 and its associated parts are the same as those shown in Figures 3 and 4. The member 176 has a downwardly depending point or end 177, which serves the purpose served by the downwardly depending hook 137 of Figures 3 and 4. It engages a part of the heating assembly when the latter rises and is raised and, to some degree, is carried by the latter in its movement upward.

Another change which is within the contemplation of our invention is the provision of means for severing the individual sausages as they are sealed or after they are sealed. One simple method of accomplishing this is to substitute a knife for the teeth 103 of the member 102. When the teeth 103 are provided they form a line of perforations running across the tape through the sealed portion. Thus the sealed portion remains on both sides of the line of perforation so that when sausages are separated the seal is not completely broken and the band remains about the sausage. When it is desired to sever the sausages so that instead of being discharged from the machine in a strip of several sausages banded together, they will be discharged as individual and individually banded sausages; the teeth 103 are made continuous so that they constitute a knife and they sever the band. This severing occurs midway of the seal so that a band remains sealed about each individual sausage, but the tape between each sausage is severed and the sausages thus emerge from the machine as individual and individually banded sausages.

The use and operation of the invention are as follows:

In the particular form here shown, the machine as above mentioned is arranged for banding sausages. When the operation is to be commenced, rolls of tape are put into the carriers,

the motor is connected with a source of current, so that it is energized, and the mechanism is driven. Obviously, it might be driven by any source of power, and is not limited to the use of an electric motor.

When the machine is driven, sausages will be put onto the chains and supported by the members 143. They will be moved from the right to left, as seen in Figures 1 and 2. The tapes will be initially fed past the sealing point over the roller 167 and onto the platform 13. As the machine operates, therefore, sausages are successively fed forward to the point of sealing. The sealing mechanism is shown in three positions, in Figures 1, 3, and 4. In Figure 1, the hook 135 is at the maximum elevated position, and the sausages may pass under it. In Figure 3 it has been lowered partly, so that it engages a sausage which is about to be closed into a loop. In this position it prevents rearward or right-hand movement of the sausage. In Figure 4, the sealing assembly has been lowered, the sausage has been forced somewhat to the left, the upper tape has been tightened about the sausage, and the sealing is taking place. In the position shown in Figure 4, the seal is either just taking place or has been finished, and the heated member 102 has emerged from the sheath 104, and has heated a transverse strip of tape, and if the teeth 103 are provided, it has perforated both bands. The perforations in the particular form shown will extend transversely with the seal strip, and will lie substantially in the middle of that strip, so that when the sausages are torn apart, they remain sealed within their loops, and a portion of the seal is therefore in place even though one sausage has been separated or torn from the other by the tearing of the strip.

The above is a general outline of the sealing operation. Mechanical movements which take place to accomplish it will now be described.

In this operation, the belt 42 drives the shaft 39, and the gear 40 on it. This gear drives the gear 43 on the shaft 44 and rotates the cam 45. The cam engages the roller 49, which is supported in the yoke 47. Thus, as the cam 45 with the cam face 46 is rotated, the plunger 51 is moved up and down, and in its up and down movement, it moves the member 61, and of course with it carries the parts 66, 67, and 68, from which the entire sealing assembly is supported, and thus as the rotor 45 rotates, through the plunger 51, it raises and lowers the sealing assembly. The sealing assembly, however, does not merely rise and fall; it swings as well, its movement being guided by the cam slot 70, and the pin 69 which engages it. It is also guided in its movement about the cam slot 70 by the dog 71, which is fixed on the pivoted lever 72. The shape of the cam slot or surface 46 is such that a portion of it is concentric with its center of rotation. This occurs as shown particularly in Figure 8, at a time when the plunger 51 is at its lowest point. When that occurs, the hook 63 rests upon the pin 64, and the weight of the sealing assembly is largely or entirely carried by that pin. The parts are shown in Figure 7 just before reaching this lowermost position and just before the sealing means has been lowered to the point where it engages the wheel 167 or the yielding members positioned on it. When it is in this position, one of the prongs of the cam 28 which rotates clockwise, as shown in Figures 7 and 8, is about to strike the cam portion 77, which is fixed in relation to the lever 76, which is itself fixed in relation to the

supporting frame of the sealing assembly. Further rotation of the cam 28 tilts the member 61 and the assembly which it carries about the pin 64, and when that occurs, the pin 69 on the portion 68 moves upwardly and to the right along the bottom of the cam groove 70 from the position of Figure 7 to the position of Figure 8. This forces the heated member 102 further down to the final position of Figure 9, in which it has emerged sufficiently from the sheath 104 to accomplish the sealing operation and to force the teeth or projections 103 through the paper or other tape material. This operation also rotates the wheel 167 through the contact of the sealing member 102 against it. It will be noticed in Figure 4 that the pivot 64 about which the sealing frame rotates is slightly below the center of rotation of the shaft 168, upon which the wheel 167 rotates, and hence as the sealing assembly is rotated from the position of Figure 3 downwardly and to the left to the position of Figure 4, it exerts an effective rotating force upon the wheel 167.

As rotation of the cam carrier 45 continues from the position of Figure 8, the cam roller 49 comes into the wider part of the groove 46, and the plunger is raised by the spring 53. When this occurs, the pin 69 moves upwardly about the groove 70 and is guided toward the upper portion of that groove by the dog 71 at the same time the member 61 and the sealing assembly which it carries swings to the left from the position of Figure 8 toward the position of Figure 7. The backward swinging movement is accomplished by the distribution of weight of the assembly and also, of course, by the shape of the cam groove 70. If desired, a spring might be inserted to assist this return swinging movement.

As the movement of the heating assembly just above described occurs, the hooks 135 and 137 carried by the member 134 also move. In its downward movement, the heating assembly does not move straight down from the position of Figure 3. It has a tilting movement to the right guided by the cam groove 70, as above described, and therefore the sheath 104 does not depress the hook 135 from the position which the latter occupies in Figure 3. However, as the heating assembly moves downwardly, the sheath 104 may have contact with the outer end of the hook 135 without depressing it, and the inclined cam face of the member 105 does contact the outer face of the hook 137 and forces that hook and the parts 134 and 128 to the left from the position of Figure 3 to the position of Figure 4. This movement is permitted by the slot 129. During this time the heating assembly, and particularly the sheath 104, has contacted the upper tape, and the heating member 102 has carried it against the lower tape to the position of Figure 4, has accomplished sealing and perforation, and has rotated the wheel 167. At the same time, the sheath has exerted pressure toward the left upon the sausage next to it, and has thus fed or tended to feed the line of sausages through the machine to the left. The sausages are held in place upon the platform 13 during this operation by the spring 140, and at the same time, the member 140 exerts a friction upon the sausages under it so that they are not forced too far to the left, which would result in an unsatisfactory seal of the next sausage. To make a proper seal, it is desirable that the sausages be held close to each other, and the spring 140 assists in accomplishing this.

As the heating assembly moves upwardly and to the right from the position of Figure 4 toward its original position of Figure 3, for example, the hook 137 is engaged on the upper surface of the member 105 and is raised by it. This of course raises the hook 135 and the member 134, and the spring 130 holds the hook 137 for awhile upon the member 105, and thus as the hooks are raised by the heating assembly, they are forced to the right by the spring 130 until the member 131 strikes the stop 138, and then further movement to the right of the hooks is prevented, and the hook 137 drops off and the parts are free to return to the position of Figure 3. As this operation has been occurring, another sausage has been moved into the position occupied by the last sausage to the right, shown in Figure 3, and thus when the hook 135 again descends, it engages that sausage and holds it in place for the next sealing operation. It also contacts the upper band 18, and to some degree depresses it.

It is obvious that the sequence of operations above described requires accurate timing. This is accomplished by proportioning the parts to bring the successive sausages into the position for banding at the time that the sealing assembly has been moved to the sealing position.

We have pointed out above the fact that the belt 42 drives the shaft 39, upon which the gear 40 is positioned. The pinion 38 is also positioned on the shaft 39, and that pinion meshes with the gear 36, which drives the gear 35. The gear 35 is fixed on the shaft 33, upon which are mounted the two sprockets 32, which drive the chains 23. The ratio of the gears in this drive is such that each time the chain is moved forward one step, or the distance necessary to feed forward another sausage, the cam carrier 45 with the cam groove 46 makes one complete revolution. As the chains are driven, the sprocket 25 is rotated by the chain 23, which engages it. This is shown in the upper position of Figure 5. The sprocket 25 is mounted on the shaft 27, which carries the cam member 28, and the drive of the cam 28 is so proportioned in relation to the drive of the cam carrier 45 with its cam groove 46 that the cam 28 makes one-third of a revolution for each full revolution of the carrier 45.

While the machine shown herewith is intended primarily for banding sausages, it might be used for banding other sorts of material, and it can be readily adjusted to accommodate different sizes of articles. The depressions formed between the successive members 143 will obviously support articles of many different sizes. To accommodate sausages or articles of different sizes, the spring assembly 140, 141 may be changed by substituting a different assembly or which may be adjusted by adjusting the member 114 up or down as described in connection with the description of Figures 3 and 4. While adjustment may be provided for the positioning of the sealing assembly to accommodate larger or smaller articles, ordinarily this is not necessary, because the sealing assembly in its upper position provides a wide clearance between it and the wheel 167, and it always moves downward to contact the wheel to accomplish sealing. Therefore, its degree of movement is sufficient to accomplish satisfactory sealing for articles which vary widely in size. The shape and travel of the members 143 is such that they will always properly position an article for sealing. As shown in Figure 3, the left-hand member 143 has carried a sausage to the proper position for sealing. Whatever the

size of the sausage or article, the position of its right-hand side or edge is always determined at substantially the same place by the member 143, which carries it and which leaves it as shown.

5 An important advantage of this machine lies in the fact that the articles which are to be banded are automatically and uniformly spaced. As stated above, the particular machine shown herewith is intended for use in banding sausages, and sausages are not entirely uniform, either as to diameter or shape, and yet it is important that they be banded together in a substantially uniform manner and at substantially uniform distances.

10 15 As shown in Figures 3 and 4, the sealing mechanism is respectively up and down. As the sealing assembly moves from the position of Figure 3 to that of Figure 4 it contacts the outer end of the member 135 and depresses sufficiently to move the sausage which is about to be banded toward the last preceding sausage, so that the distance between two sausages becomes substantially the same as the distance between other preceding sausages.

20 25 In the modified form of Figure 14, the spring member is elongated so that instead of the relatively short spring member 135 there is provided the longer and preferably more flexible member 173, and this member, as shown, is depressed by the sealing assembly. When the sealing assembly has moved to the full sealing position, a portion of the spring member 173 lies between the sheath of the sealing member and the tape.

30 35 Whichever form of the spring member is used the pinching of the sausage which is about to be sealed is effected and controlled largely by the sealing assembly which as it descends moves the sausage as far as possible to the left. In effect, the inclined surface of the member 104 has a 40 camming action against the sausage and forces it to the left, and this is true whether or not the spring member 135 or 173 is used. One effect of the member 173 is that it overlies the sausage and should an extremely inaccurate or curved 45 sausage be present, the spring 173 will be contacted first by the sealing assembly as it descends and will prevent a pinching or breaking of the sausage the spring 173 thus shields and protects the sausage.

50 55 While we have spoken above of the uniformity with which the sausages are placed, it is to be understood that absolute mechanical uniformity is impossible with articles which are themselves non-uniform. In general, the sausages are 60 banded together so that they are absolutely or practically in contact with each other in the complete article. As shown in Figures 3 and 4 in particular in the completed band of sausages, the various sausages are substantially or actually in contact with the adjacent sausages. The sealed portion between each article is of such size that except in the case of very small sausages it would not hold the sausages apart or serve to separate them. Ordinarily, as shown in Figures 3 and 4, 65 adjacent sausages are in contact with each other. In general therefore, in spacing the sausages, a minimum space is provided between adjacent sausages and this minimum space is within limits substantially uniform. The sealing assembly as it 70 moves toward the sealing position serves therefore to move the sausages to be sealed toward the last previously sealed sausages and to accomplish a uniform positioning of the sausages, so that as far as possible, waste of space is eliminated and 75 the sausages are brought into contact or substan-

tially into contact with each other when they are thus sealed into position by the tape.

We claim:

1. In combination with an article banding machine, article carrying means, a plurality of band supplying means adapted to supply a plurality of bands to said articles on opposite sides thereof, a movably mounted sealing assembly including a heating element and means for moving said sealing assembly toward said bands to contact and to seal two of said bands together, said sealing means being movable against the article to move the latter into properly placed relation with respect to the last previously sealed article, said sealing means being arranged to move at an angle to the horizontal and to the vertical and being provided with a member adapted to move said article which is about to be banded.

2. In combination with an article banding machine, article carrying means, a plurality of band supplying means adapted to supply a plurality of bands to said articles on opposite sides thereof, a movably mounted sealing assembly including a heating element and means for moving said sealing assembly toward said bands to contact and to seal two of said bands together, said sealing means being movable against the article to move the latter into properly placed relation with respect to the last previously sealed article, said sealing means being arranged to move at an angle to the horizontal and to the vertical and being provided with a member adapted to move said article which is about to be banded, the said member, which moves the article, comprising a sheath movably positioned about said heating element.

3. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, means for moving said head against said abutment and against the two bands as they pass over the abutment, and means for holding the articles to be secured out of the line of movement of said sealing head.

4. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, means for moving said head against said abutment and against the two bands as they pass over the abutment, and means for holding the articles to be secured out of the line of movement of said sealing head including a movably mounted article retaining member having an end portion located adjacent the path of movement of the sealing head and adapted to engage the articles after they have passed beyond the line of movement of said sealing head.

5. In combination, in means for securing articles between bands, means for moving a pair of bands along separate but adjacent paths, means

for moving the articles to be secured into and along the space between said bands, a movable abutment located beneath the paths of movement of said bands and articles and having a smooth surface adapted to engage the lowest of said bands, a sealing head including a sealing element and means for heating it, said sealing head being movably mounted, means for moving said head against said abutment and against the two bands as they pass over the abutment, and means for holding the articles to be secured out of the line of movement of said sealing head, including a movably mounted article retaining member having an end portion located against the path of movement of the sealing head and adapted to engage the articles after they have passed beyond the line of movement of said sealing head.

6. In combination, in means for securing articles between bands, means for moving a pair of bands along separate but adjacent paths, means for moving the articles to be secured into and along the space between said bands, a movable abutment located beneath the paths of movement of said bands and articles and having a smooth surface adapted to engage the lowest of said bands, a sealing head including a sealing element and means for heating it, said sealing head being movably mounted, means for moving said head against said abutment and against the two bands as they pass over the abutment, and means for holding the articles to be secured out of the line of movement of said sealing head, including a movably mounted article retaining member having an end portion located adjacent the path of movement of the sealing head and adapted to engage the articles after they have passed beyond the line of movement of said sealing head, said abutment being movable in response to the movement of the band thereacross.

7. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, means for moving said head against said abutment and against the two bands as they pass over the abutment, means for holding the articles to be secured out of the line of movement of said sealing head, and a fixed article support located beyond said abutment and having a supporting surface over which the attached articles are movable.

8. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, and means for moving said head against said abutment and against the two bands as they pass over the abutment, means for holding the articles to be secured out of the line of movement of said sealing head, a fixed article support located beyond said abutment and having a supporting surface over which the attached

articles are movable, and yielding means for holding said articles movably in contact with said fixed article support after they have passed beyond said abutment and beyond the path of movement of the sealing head.

9. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, means for moving said head against said abutment and against the two bands as they pass over the abutment, and means for imparting feeding movement to the secured articles and thus to the bands, in response to the movement of the sealing head.

10. In combination, in means for securing articles between bands, means for moving a pair of bands along separate but adjacent paths, means for moving the articles to be secured into and along the space between said bands, an abutment located beneath the paths of movement of said bands and articles and having a surface adapted to engage the lowest of said bands, a sealing head including a sealing element and means for heating it, said sealing head being movably mounted, means for moving said head against said abutment and against the two bands as they pass over the abutment, and means for imparting feeding movement to the secured articles and thus to the bands, in response to the movement of the sealing head toward the abutment.

11. In combination, in means for securing articles between bands, means for conveying the articles along a predetermined path, an abutment over which said articles pass in the course of said movement, means for feeding a pair of bands across said abutment and about said articles, means for sealing said bands together about said articles including a sealing head and means for moving it toward and away from said abutment, means for holding said articles out of the line of movement of said head, and means for imparting movement step by step to the sequence of attached articles and for thereby moving said bands through the space between said abutment and said sealing head.

12. In combination, in means for securing articles between bands, means for conveying the articles along a predetermined path, an abutment over which said articles pass in the course of said movement, means for feeding a pair of bands across said abutment and about said articles, means for sealing said bands together about said articles including a sealing head and means for moving it toward and away from said abutment, means for holding said articles out of the line of movement of said head, means for imparting movement step by step to the sequence of attached articles and for thereby moving said bands through the space between said abutment and said sealing head, and means for maintaining a timed relationship between the movement of the sealing head and the movement of the articles being fed and for moving the sealing head into sealing position once between each two adjacent articles as the articles are successively moved to and away from the point of sealing.

13. In a heat sealing assembly for use in ma-

chines for securing articles between heat sealable bands, an abutment, means for feeding the bands over said abutment with the articles to be secured between the bands, a movably mounted sealing assembly located adjacent said abutment including a heated element and a sheath therefor, said sheath normally projecting beyond said heated element but being retractable relative thereto, said heated element having band perforating members projecting therefrom within the sheath, and means for moving said sealing assembly toward said abutment and bands to contact one of said bands and force it into contact with the other and to seal the two together and perforate them, said sheath engaging an article to move the same forwardly upon movement of said sealing assembly.

14. The method of securing articles together in a unitary package including supporting strips connected together about and between the articles, which includes feeding the articles to be secured successively step by step and in spaced relationship along a predetermined path toward a securing zone, feeding a plurality of strips toward the securing zone along converging but initially separated paths with said paths converging, about the path of movement of the articles, toward the securing zone, securing said strips together in the securing zone in advance of each article to be secured, moving each article to be secured into contact with the previously secured article to cause both articles and the strips to advance until the article to be secured has passed beyond the securing zone, thereafter securing said strips in the securing zone behind said article to be secured and continuing said steps until the desired number of articles has been secured between said strips.

15. In combination, in a machine for securing articles together in packages including supporting strips extending about and connected together between the articles, an endless conveyor, means for actuating said conveyor, said conveyor including a plurality of links and supporting fingers mounted on said links and spaced transversely apart on said links, said supporting fingers including portions forming seats adapted to receive the ends of elongated articles, means for guiding said securing strips along paths converging about the path of movement of the articles on the conveyor, means for supplying to said strip guiding means strips having a width less than the space between the fingers of said links, means for securing said strips together between each pair of adjacent articles and means for supporting the secured articles and the strips as the articles are successively secured together.

16. In combination, in a machine for securing articles together in packages including supporting strips extending about and connected together between the articles, an endless conveyor, said conveyor including a plurality of links and supporting fingers mounted on said links and spaced transversely apart on said links, said supporting fingers including portions forming seats adapted to receive the ends of elongated articles, means for guiding securing strips along paths converging about the path of movement of the articles on the conveyor, means for supplying to said strip guiding means strips having a width less than the space between the fingers of said links, means for supporting said strips including a drum located adjacent one end of the conveyor, one strip, as it passes across the face of said

drum, intersecting the path of movement of the articles on said conveyor, and means for securing said strips together between each pair of adjacent articles including a movable sealing head and means for moving said head toward and away from said drum.

17. In combination, in a machine for securing articles together in packages including supporting strips extending about and connected together between the articles, an endless conveyor, means for actuating said conveyor, said conveyor including a plurality of links and supporting fingers mounted on said links and spaced transversely apart on said links, said supporting fingers including portions forming seats adapted to receive the ends of elongated articles, means for guiding securing strips along paths converging about the path of movement of the articles on the conveyor, means for supplying to said strip guiding means strips having a width less than the space between the fingers of said links, means for securing said strips together between each pair of adjacent articles to be secured, including an anvil adjacent a bight of said conveyor and of less width than the space between the fingers on said links, the surface of said anvil intersecting the path of movement of the articles delivered by said conveyor, said strip guiding means being adapted to guide said strips across said anvil and about the articles delivered from said conveyor, and a securing head and means for moving it toward and away from said anvil and against said strips.

18. In combination, in a machine for securing articles together in packages including supporting strips extending about and connected together between the articles, a generally cylindrical anvil mounted for rotation about a horizontal axis, means for delivering a strip of material to said anvil for movement with and about the same, means for delivering above said strip on said anvil, in spaced succession, a plurality of articles of substantially greater length than the width of the strip, means for delivering above said articles and above the anvil a second securing strip overlying the first, and means for securing said strips together between each adjacent pair of articles to be secured including a sealing head and means for moving said sealing head toward and away from said anvil and against said sealing strips.

19. In combination, in a machine for securing articles together in packages including supporting strips extending about and connected together between the articles, a generally cylindrical anvil mounted for rotation about a horizontal axis, means for delivering a strip of material to said anvil for movement with and about the same, means for delivering above said strip on said anvil, in spaced succession, a plurality of articles of substantially greater length than the width of the strip, means for delivering above said articles and above the anvil a second securing strip overlying the first, and means for securing said strips together between each adjacent pair of articles to be secured including a sealing head and means for moving said sealing head toward and away from said anvil and against said sealing strips, and means for holding the adjacent articles to be secured out of line with the path of movement of said sealing head.

20. In combination, in means for packaging articles by securing them between strips, a rotary anvil, means for passing a pair of strips toward and across said anvil along converging paths,

means for delivering the articles to be secured to the space between said converging strips, means for securing the strips together about said articles, including a securing head and means for moving said securing head, against said strips, toward and away from said anvil, and means for keeping the articles to be secured out of the line of movement of said securing head.

21. In a machine for banding articles, means for supplying banding material to a point in the machine at which portions of the material are adapted to be secured together about each article in turn, means for feeding a plurality of articles one at a time to said point, and banding mechanism including means for first wrapping a portion of the material about the article into overlying relation to another portion of the material and then securing said portions together at said point, a portion of said banding mechanism engaging with the article to move the latter into properly placed relation with respect to the previously banded article prior to securing said portions of banding material together said last named means having a surface engageable with the article to feed the same, and means to advance said surface in a direction to feed the article.

22. In a machine for banding articles, means for supplying banding material, a rotary platen across which portions of the banding material are adapted to be positioned while being secured together, means for feeding each of the articles to be banded into a position adjacent the platen with portions of the banding material about the article and other portions of the banding material across the platen, and a reciprocating sealing head which is movable into engagement with the platen behind the article on the interposed portions of the banding material for securing such portions together.

23. In a machine for banding articles, means for supplying banding material, a rotary platen across which portions of the banding material are adapted to be positioned while being secured together, means for feeding each of the articles to be banded into a position adjacent the platen with portions of the banding material about the article and other portions of the banding material across the platen, and a sealing head which is movable into engagement with the platen behind the article on the interposed portions of the banding material for securing such portions together, said sealing head and platen moving forwardly together in fixed relation to one another while in engagement with each other during the securing operation.

24. In a machine for banding articles, means for supplying banding material, a platen across which portions of the banding material are adapted to be positioned while being secured together, means for feeding each of the articles to be banded into a position adjacent the platen with portions of the banding material about the article and other portions of the banding material across the platen, a support beyond the platen for receiving the articles after they have been banded, and a sealing head which is movable into engagement with the platen behind the article on the interposed portions of the banding material for securing such portions together, said sealing head being movable into engagement with the platen along a path of movement which is inclined with respect to the surface of said support.

25. In a machine for banding articles, means

for feeding a plurality of the articles, means for supplying banding material, a platen across which portions of the banding material are adapted to be positioned while being secured together, a sealing head which is movable into engagement with the platen behind one of the articles on the interposed portions of the banding material for securing such portions together, and means engageable with the article for holding the same in proper position while the portions of the material are being secured together.

26. In a machine for banding articles, means for feeding a plurality of the articles, means for supplying banding material, a platen across which portions of the banding material are adapted to be positioned while being secured together, a sealing head which is movable into engagement with the platen behind one of the articles on the interposed portions of the banding material for securing such portions together, and means engageable with the article for holding the same in proper position while the portions of the

5
10

material are being secured together, and a support beyond the platen for receiving the articles after they have been banded.

Certificate of Correction

Patent No. 2,418,054.

March 25, 1947.

EDWARD C. SLOAN ET AL.

It is hereby certified that errors appear in the printed specification of the above numbered patent requiring correction as follows: Column 10, lines 58 and 59, strike out the words "and the heating member 102" and insert the same after the comma and before "has" in line 60, same column; and that the said Letters Patent should be read with this correction therein that the same may conform to the record of the case in the Patent Office.

Signed and sealed this 21st day of October, A. D. 1947.

[SEAL]

THOMAS F. MURPHY,
Assistant Commissioner of Patents.
